UNITED STATES PATENT OFFICE.

ALBERT M. PARISH, OF CHICAGO, ILLINOIS.

WINDOW-SASH HOLDER.

1,128,181.

Specification of Letters Patent.

Patented Feb. 9, 1915.

Application filed June 11, 1914. Serial No. 844,459.

To all whom it may concern:

Be it known that I, ALBERT M. PARISH, a citizen of the United States, and a resident of the city of Chicago, county of Cook, and State of Illinois, have invented certain new and useful Improvements in Window-Sash Holders, as set forth in the annexed specification.

My invention relates to devices used in conjunction with window sashes for holding the latter against vibration, and has for its object the production of a device of this character which will be of durable and economical construction and efficient in use.

Other objects will appear hereinafter.

With these objects in view my invention consists in the combinations and arrangements of parts hereinafter described and claimed.

The invention will be best understood by reference to the accompanying drawings forming a part of this specification, and in which—

Figure 1 is a vertical transverse section through the lower portion of a window frame and sashes equipped with a sash holder embodying my invention, Fig. 2 is a section taken on substantially line $x-x$ of Fig. 1, Fig. 3 is an enlarged perspective view of the holder proper detached, Fig. 4 is a detail section through the lower end of said holder, Fig. 5 is a section similar to Fig. 1 illustrating the device arranged in a different position from that shown in Figs. 1 and 2, Fig. 6 is a fragmental front elevation of the construction shown in Fig. 5, Fig. 7 is a view similar to Fig. 5 illustrating another form of my invention, and Fig. 8 is a fragmental front elevation of the construction shown in Fig. 7.

The preferred form of construction as illustrated in the drawings comprises an elongated substantially rectangular member 1 formed of flexible material and preferably of hickory wood. The member 1 fits snugly in a slot 2 provided for the reception thereof in the front side of the window sash 3 in conjunction with which the device is employed, adjacent each of the vertical edges of said sash, as clearly shown in the several views. Coöperating with the member 1 is a rod 4, the lower end of said rod projecting loosely through perforations 5 provided in enlargements or projections 6 formed at the respective ends of member 1

at the rearward side thereof. The lower extremity of the rod 4 is provided with a head 7 which engages against the under side of the lower enlargement or projection 6 as clearly shown in Fig. 4.

With the arrangement set forth it will be seen that, upon upward drawing of the rod 4, the lower end of the member 1 will be correspondingly drawn upwardly causing flexing of said member in the manner illustrated in Fig. 3. Such flexing of said member will cause the central portion thereof to engage against the adjacent side of the sash groove 8 of the sash frame with the desired result of holding the sash against vibration as will be readily understood. This upward drawing of the rod 4 in order to flex the same is effected by means of a nut 9 which is threaded upon the upper end of said rod, said end of said rod protruding above the upper edge of the window sash for this purpose. Said nut engages against a rubbing plate 10 secured to the upper edge of the sash, the arrangement being such, as will be seen, that upon positive rotation of said nut, the rod 4 will be drawn upwardly as is obvious. The upper end portion of the rod 4 is inclined inwardly slightly in order to space the nut 9 from the adjacent edge of the sash 3 or groove 8 so as to permit of said nut being more readily engaged by the fingers. With this arrangement then it will be seen that vibration of the window sash may be prevented by simply adjusting the nuts 9 coöperating with the members 1 arranged at the opposite edges of the sash.

In the construction shown in Figs. 5 and 6 the member 1 is mounted in a slot 11 provided in the window frame or in the side of the sash groove 8 which registers with the front side of the window sash 3. The rod 4 which coöperates with the member 1, in this arrangement, projects upwardly through the sash groove strip, the upper end portion of said rod being inclined inwardly so as to project from the inner side of said strip as shown. The nut 9 coöperating with the upper end portion of the rod 4, in this form, engages against a plate 12 secured to the window frame. The operation of the member 1 is the same as that before described except that in this arrangement said strip will engage against the window sash whereas in the first described arrangement said member was carried by

the window sash and engaged against the side of the sash groove. The result as to the prevention of the vibration of the window sash is the same in each arrangement.

5 In the form shown in Figs. 7 and 8 the member 1 is mounted in a housing 13 which is secured by screws 14 to the sash frame so that said member 1 is adapted for engagement with the front side of the window 10 sash very much in the same manner as in the arrangement just described shown in Figs. 5 and 6. The operation is precisely the same in each arrangement, it being clear that in each case, flexing of the member 1 15 is effected by adjustment of the nut 9. The last arrangement is in the nature of an attachment being designed for use upon old buildings. The other two forms or arrangements are designed to be applied simultaneously 20 with the installation of the window although any of the forms described may be readily and easily applied to a window already installed.

While I have illustrated and described 25 the preferred forms of construction for carrying my invention into effect, these are capable of variation and modification without departing from the spirit of the invention. I, therefore, do not wish to be limited 30 to the precise details of construction set forth, but desire to avail myself of such variations and modifications as come within the scope of the appended claims.

Having described my invention what I 35 claim as new and desire to secure by Letters Patent is:

1. The combination with a window frame and a sash mounted therein, of a flexible member coöperating with said sash and 40 adapted, when flexed, to clamp said sash against vibration in said frame; and means for flexing said member, said means, in the flexing operation, being movable in a direction at substantially right angles to the

direction of flexing of said member, substantially as described.

2. The combination with a window frame and a sash mounted therein, of an elongated flexible member coöperating with said sash and adapted, when flexed, to clamp said sash against vibration in said frame; and manually operable means adapted to exert a pressure on said member in a direction longitudinally of said member for flexing the latter, substantially as described. 55

3. The combination with a window frame and a sash mounted therein, of an elongated flexible member coöperating with said sash adapted, when flexed, to clamp said sash against vibration in said frame; and a rod 60 extending substantially parallel with said member and engaging against one end thereof whereby a pressure may be exerted on said member in a direction longitudinally of said member to flex the latter, substantially as described. 65

4. The combination with a window frame and a sash mounted therein, of an elongated flexible member coöperating with said sash adapted, when flexed, to clamp said sash 70 against vibration in said frame, said member being held against relative longitudinal movement; projections at one side of said member at the ends thereof; and a rod extending substantially parallel with said 75 member and engaging with said projections whereby a pressure may be exerted on said member in a direction longitudinally of said member to flex the latter, substantially as described. 80

In testimony whereof I have signed my name to this specification in the presence of two subscribing witnesses.

ALBERT M. PARISH.
